UNITED STATES PATENT OFFICE.

HENRY F. SEARLES, OF HOPEDALE, MASSACHUSETTS, ASSIGNOR TO DRAPER COMPANY, OF PORTLAND, MAINE, AND HOPEDALE, MASSACHUSETTS.

COPYING-PRESS.

SPECIFICATION forming part of Letters Patent No. 760,652, dated May 24, 1904.

Application filed November 12, 1903. Serial No. 180,846. (No model.)

To all whom it may concern:

Be it known that I, HENRY F. SEARLES, a citizen of the United States, residing at Hopedale, in the county of Worcester and State of Massachusetts, have invented an Improvement in Copying-Presses, of which the following description, in connection with the accompanying drawings, is a specification, like characters on the drawings representing like parts.

This invention has for its object the production of a novel and efficient apparatus for making press-copies of letters or other documents which are written, printed, or type-written in a copying medium; and my invention relates more particularly to that type of copying apparatus wherein the copy is made on an automatically-dampened sheet in web form. In such apparatus the copy-taking web is dampened and moved longitudinally between a rotatable impression-roll or platen and a pressure-roll, the document to be copied being passed between the pressure-roll and platen with its face in contact with the dampened web. Subsequently the latter may be cut into short sheets for convenience in filing away. This type of copying-press makes one copy at a time.

My present invention is so constructed and arranged that two copies are made of an original each time the latter is passed through the press, so that two separate and distinct records may be kept of all documents copied. To this end a transfer sheet or web and a record sheet or web are used, the impression from the original being first made upon the transfer-web as a negative, and the record-web is then brought into contact with such negative impression under pressure to receive a positive copy thereof. The record-web is preferably stout paper suitable for filing and capable of standing considerable handling for purposes of reference, while the transfer-web is made of tissue or other transparent thin paper, so that the impression-copy can be read through it and used as a second permanent record.

The various novel features of my invention will be fully described in the subjoined speci-

fication, and particularly pointed out in the following claims.

50

Figure 1 is a side elevation of a copying-press embodying one form of my present invention and showing the actuating means therefor. Fig. 2 is a central longitudinal sectional view thereof. Fig. 3 is a diagrammatic view showing the paths of movement of the transfer and record webs through the press, and Fig. 4 is an enlarged detail to be referred to.

55

Two upright parallel sides A of suitable size and shape to sustain the operative parts are rigidly secured to a base A', having an opening A^x, Fig. 2, to constitute the frame. The sides are vertically slotted at a to receive bearing-blocks b for the journals b^x of a roll B, termed the "primary pressure-roll." Each slot has a cover-plate a', provided with a threaded hole to receive a pressure-screw 5, bearing against the top of the adjacent bearing-block b to regulate the pressure between the roll B and the platen-roll to be described. A tie-rod a^x connects the high portions of the sides to impart requisite rigidity thereto. The impression or platen roll P is located below the primary roll B and in contact therewith, 75 its journals p being extended through bearing-holes in the sides A, one of the journals being prolonged and having secured to it outside the frame an internal annular gear p^x, Fig. 1. The rolls B and P have a yielding surface—80 as, for instance, india-rubber—so that the portions thereof in contact will be somewhat flattened to increase the action thereof in making a copy from the original document. A feed table or shelf f is supported on and between the sides A opposite and adjacent the nip of rolls B and P, Fig. 2, to support the original document D as it is fed to the rolls. On the opposite side of the latter a delivery table or shelf f' is mounted, its inner end being downcurved at f^x and to closely approach the periphery of the impression-roll P to receive the document D after it has passed between the rolls. Below and at the left of the roll P a water-tank M is supported on the base A', and arms m are upturned at their

85

90

95

lower ends to support a guide-roll m^x slightly above the bottom of the tank, the upper ends of the arms being hooked at m' to engage the end of the tank.

5 Brackets A^2 on the sides A sustain journals t^x of a roll T of thin tissue or other suitable transparent paper, the free end of which web is led over the end of the tank M and under the roll m^x to immerse it in the water, and I 10 term this the "transfer" web or sheet. From the tank the web t is carried around the impression-roll P and between it and the primary pressure-roll B; but it is first subjected to the squeezing action of a wringer-roll W, held 15 against roll P by screws 6, extended through threaded holes in lateral ears a^6 , crossing horizontal guide-slots a^7 in the sides. Bearing-blocks a^8 are mounted in the slots and support the journals w of the roll W, the inner ends 20 of the pressure-screw 6 bearing against said blocks to regulate the pressure between the platen-roll and the wringer-roll W. As the wet web t passes between such rolls the surplus moisture is squeezed out of it, so that it 25 is properly damp when it moves under the primary pressure-roll B. When the document D to be copied is fed face down between rolls B and P, its face is pressed against the dampened transfer-web t and a reverse or 30 negative copy is made thereon. The document D is drawn through by rotation of the impression or platen roll P and delivered upon the table f' , while the impressed transfer-web continues around the platen-roll and between 35 it and a secondary pressure-roll C, Fig. 2, and thence down through the opening A^x in the base A'. Referring to Fig. 1, the journals c of the roll C extend loosely through large holes a^{10} in the sides (see dotted lines, 40 Figs. 1 and 4) and enter upright bearing-bars c' . Lugs a^{12} project from the sides above and below the roll C and have threaded holes for adjusting-screws 8, each having an annular groove 9, (see Fig. 4,) entered by a pin 10 in 45 the bar c , so that the screw is rotatably coupled to said bar. By setting up or slackening off the screws 8 the roll C will be moved toward or from the platen-roll P to vary the pressure between them. A check-nut a^{13} may be 50 used on each adjusting-screw to firmly hold it in adjusted position, and it will be manifest that by the devices described the roll C is securely held in a fixed position.

As shown in Fig. 2, a second water-tank N 55 is mounted on the base at the right of the opening A^x , said tank having therein a roll n^x , supported by arms n , hooked over the outer end of the tank at n' . The journals r^x of a roll R of record-paper, preferably of 60 stout strong texture, are supported in upright notches a^{15} , the end r of the web being led into the tank beneath roll n^x and then up over the roll C and down between it and the platen-roll in contact with the transfer-web at that 65 point.

A wringer-roll W' is mounted adjacent the secondary pressure-roll C and in contact therewith to squeeze out the surplus moisture from the record-web as it passes between rolls W' and C. Pressure-regulating screws 20, 70 supported in ears a^{20} on the sides, act against the bearing-blocks a^{21} , which latter are slidably mounted in slots a^{22} in the frame sides. By means of these screws the pressure between rolls C and W' is regulated entirely independent of the pressure between the rolls C and P, as will be manifest. 75

Remembering that the transfer-web t has received upon its outer face a negative impression or copy from the original document 80 D, it will be manifest that such impressed face will be brought into contact with the dampened record-web r as the two webs are carried between the platen-roll P and the secondary pressure-roll C, and by this pressure 85 a positive impression or copy will be transferred from the transfer-web to the record-web. Thus two copies of the original are obtained, one a negative on the web t and the other a positive on the web r , and the former 90 copy can be easily read from the opposite face of web t owing to its transparency. After a number of documents have been copied the two webs can be cut transversely into sheets for filing away in suitable receptacles. 95

Referring to Fig. 1, a bracket A^5 is secured to the exterior of one of the sides A, it having an upright bearing-car a^{30} for the short shaft a^{31} of a crank-arm a^{32} , the inner end of the shaft having secured to it a pinion a^{33} , in 100 mesh with the internal gear p^x . By rotating the crank-arm in the direction of arrow 50 the impression or platen roll P will be rotated in the same direction, but at a slower speed, and such rotation of the platen-roll 105 causes rotation of the pressure-rolls and wringer-rolls in the direction of the arrow on Fig. 2.

In the diagram view Fig. 3 the rolls are omitted and only the paths of the two webs are 110 shown, that of the transfer-web t by a dotted line and that of the record-web r by a full line to more clearly show the mode of operation of the press.

The operation of the press is rapid, it makes 115 the required copies accurately and evenly, and the dampening of the two webs can be regulated with great nicety.

Having fully described my invention, what I claim as new, and desire to secure by Letters 120 Patent, is—

1. In a copying-press for making at one operation two copies of an original, means to impose an impression from the original upon a transparent transfer-sheet, means to transfer 125 to a record-sheet a positive copy from the impressed face of the transfer-sheet, and devices to dampen both the transfer and record sheets.

2. In a copying-press for making at one operation two copies of an original, means to im- 130

pose an impression from the original upon a transparent transfer-sheet, means to transfer to a record-sheet a positive copy from the impressed face of the transfer-sheet, an impression-roll forming a common member of both of said means, a separate and independently-adjustable pressure-rolls coöperating therewith to impress the transfer and record sheets respectively, and devices to dampen both the transfer and record sheets.

3. In a copying-press, a platen or impression roll, two independently-adjustable pressure-rolls coöperating therewith, means to dampen a transfer-web adapted to be carried around the platen-roll between it and both pressure-rolls, passage of the original document between one of the latter rolls and the platen-roll and facing the transfer-web making an impression thereon, a delivery device to remove the document when such impression has been made, and means to carry a damped record-web between the other pressure-roll and the platen and against the impressed face of the transfer-web, to transfer to the record-web a positive copy from the impressed face of the transfer-web.

4. In a copying-press, a platen-roll and two coöperating pressure-rolls, means, including a wringer-roll coöperating with the platen-roll, to dampen a transfer-web adapted to be carried around the platen-roll and between both pressure-rolls, means, including a wringer-roll coöperating with a pressure-roll to dampen a record-web and carry it between one of the pressure-rolls and the platen-roll in contact with the previously-impressed face of the transfer-web, and means to direct the matter to be copied between the other pressure-roll and the platen-roll and facing the damped transfer-web, to make an impression thereon of the matter to be copied, a copy of such impression being subsequently transferred to the record-web.

5. In a copying-press, means to impose an impression from an original upon a transfer-sheet, devices to dampen the latter, means to transfer to a record-sheet a positive copy from the impressed face of the transfer-sheet, independent devices to dampen the record-sheet, a rotatable platen forming a member of both of said means, actuating mechanism for said platen, a device to deliver the original document after the impression has been made upon the transfer-sheet, and supports located at opposite sides of the platen to sustain respectively rolls of transfer and record paper.

6. In a copying-press, a rotatable platen-roll, a wringer-roll and primary and secondary pressure-rolls peripherally arranged around and driven by rotation of the platen-roll, means to positively rotate the latter, a second

wringer-roll coöperating with the secondary pressure-roll, means to support a roll of transfer-paper at one side of the rolls, means to support a roll of record-paper at the other side thereof, a wetting device for each web of paper, and means to introduce a document to be copied between the platen-roll and the primary pressure-roll, and a delivery device for such document, a negative being first imposed upon the transfer-web and thereafter a positive from such negative is transferred to the record-web.

7. In a copying-press for making at one operation two copies of an original document, means to impose a negative impression from an original document, upon a transfer-web of tissue-paper, means to transfer to a record-web of paper a positive copy from such negative impression, separate and independently-adjustable means to dampen the webs, and means to carry the webs through the press to successively form the negative and positive copies of the matter to be copied.

8. In a copying-press, a platen-roll having a yielding surface, independently-adjustable primary and secondary pressure-rolls coöperating therewith, a wringer-roll coöperating with the platen-roll, a second wringer-roll coöperating with the secondary pressure-roll, each wringer-roll being adjustable, a dampening device adjacent each wringer-roll, and means to operate the press by or through the platen-roll, a damped transfer-web being carried around the platen-roll to receive beneath the primary pressure-roll a negative impression from the matter to be copied, and a damped record-web being carried around the secondary pressure-roll between the adjacent wringer-roll and the platen-roll, successively, to receive a positive copy of the negative impression on the transfer-web.

9. In a copying-press for making at one operation two copies of an original, a platen-roll and a coöperating pressure-roll, both having a yielding surface, means to dampen a transfer-web adapted to pass between said rolls and receive a copy from the face of the original document, a second pressure-roll, and means to direct a damped record-web between it and the impressed face of the transfer-web as the latter only is carried around the platen-roll, to transfer a positive copy of such impression to the record-web.

In testimony whereof I have signed my name to this specification in the presence of two subscribing witnesses.

HENRY F. SEARLES.
